UNITED STATES PATENT OFFICE.

DON CARLOS TRAVIS, OF KENOSHA, WISCONSIN, ASSIGNOR TO SIMMONS COMPANY, OF KENOSHA, WISCONSIN, A CORPORATION OF DELAWARE.

BEDSTEAD.

1,396,476.

Specification of Letters Patent.

Patented Nov. 8, 1921.

Application filed May 15, 1918. Serial No. 234,643.

To all whom it may concern:

Be it known that I, DON CARLOS TRAVIS, a citizen of the United States, residing at Kenosha, in the county of Kenosha and 5 State of Wisconsin, have invented certain new and useful Improvements in Bedsteads, of which the following is a specification.

My invention relates to Improvements in bedsteads and particularly to bedsteads constructed of steel or other metal.

The principal objects of the invention are to provide a metal bedstead equipped with improved means for connecting together the head and foot ends of the bedstead and for 15 supporting the bed bottom or spring; to provide a metal bedstead of the so-called three-piece type, which may be constructed of relatively cheap material, for instance odd lengths of angle irons of standard dimensions; to provide an improved construction 20 in which the various parts are rigidly and securely and at the same time detachably connected together; to provide an improved metal bedstead which shall be neat in appearance and efficient and practical in use, 25 and in general to provide an improved bedstead of the character referred to.

In the drawings which illustrate a preferred embodiment of my invention, Figure 30 1 is a perspective view of a light steel bedstead constructed according to my invention.

Fig. 2 is a view of one of the corner connections looking from the inside of the bedstead;

Fig. 3 is a view similar to Fig. 2 but showing only that part of the corner connection which is integral with the bed bottom supporting frame;

Fig. 4 is a vertical section through the bed 40 post and parts connected thereto which are illustrated in Fig. 2;

Fig. 5 is a section taken on the line 5—5 of Fig. 2;

Fig. 6 is a section taken on the line 6—6 45 of Fig. 2;

Fig. 7 is a section taken on the line 7—7 of Fig. 2.

Referring to the drawings, 10 is the foot end and 11 is the head end of a steel bedstead which comprises three principal parts, 50 the other part being the mattress frame to which the bed fabric 12 is connected and which also serves as a connection between the foot and head ends of the bedstead. The 55 principal parts of the mattress frame com-

prise a pair of side members 13, these in the present instance being constructed of medium gage iron or steel tubing of oval-cross-section as shown best in Fig. 6.

The ends of the side members 13 are flattened out as indicated at 14 and are inserted through slots punched in the vertical flanges 15 of vertically extending angle iron members 16. The said angle members 16 are connected to the flattened ends 14 of the 60 side tubes 13 by means of rivets 17 and the tubes 13 and the angle iron 16 are maintained in the proper right angle relation by means of obliquely extending braces 18.

The lower end of each of these braces 18 70 is riveted to the side of the tube 13 as shown at 19 and the upper end of the said brace 18 is united by a rivet 20 to a subsidiary length of angle iron 21, the latter being rigidly united to the principal angle member 16 by 75 means of a pair of rivets 22.

The mattress or spring in the present instance takes the form of a wire link fabric 12 which by means of end helicals 23 is connected and stretched between a pair of cross 80 pieces 24 which in the present instance comprise two transversely extending angle irons. The horizontal flange of each of the angle irons 24 is supported on the tops of the vertical angle members 16 and 21 and is maintained in position by means of a pair of lugs 25 and 26 projecting respectively from the angle members 16 and 21 through suitably spaced vertical slots punched in the vertical flange 27 of the said cross angle 24. By reason of the lugs 25 and 26 being spaced apart a considerable distance, the cross angle 24, which is subject to the heavy tension of the helicals 23 seats itself firmly on the said lugs and all tendency of the mattress frame to assume a diamond or oblique shape is prevented. Thus when the mattress frame unit 85 is removed from the head and foot ends of the bedstead, it will maintain its shape without the use of extraneous bracing.

Describing the detachable connection between the mattress frame unit and the ends of the bedstead, it will be observed that the wall of the bed post 28 is apertured to admit the reduced end of a loop 29 of steel or other metal, said loop being provided on its outer end with shoulders 30 adapted to engage against the outer surface of the post. Owing to the fact that the tubular bed post 28 is constructed of comparatively thin metal, 110

I find it advisable to interpose between the shoulder ends 30 of the loop 29 and the wall of the bed post, a plate or washer 31 which in the present instance takes the form 5 of an angle iron, the outwardly extending flange 32 of which serves to conceal the details of the detachable connection.

The loop 29 is drawn inwardly so as to hold the shoulder ends 30 against the post 10 by means of a folded steel tapered wedge 33 which is of the proper cross-section to substantially fit the interior of the loop 29. In this instance I also find it advisable to insert an inner washer or plate 34 between the 15 wedge 33 and the wall of the tubular post 28.

The outwardly projecting parts 35 of the loop 29 are united together or bridged by a transverse pin or rivet 36, the latter preferably having its ends headed over as shown at 20 37 so as to maintain it securely into position in the loop. Said transversely extending member or pin 36 serves as an abutment for wedging means carried by the mattress unit, the other abutment comprising the outwardly 25 facing surface of the plate or angle iron 31. The wedging means carried by the mattress unit are provided by cutting, in the longitudinal extending flange of the angle iron member 16, an open oblique slot 38 the depending tongue or lug 39 formed thereby being arranged to wedge behind the pin 36 previously referred to. It will be seen that the intermediate portion of the edge of the angle iron member 16 which engages the 30 post is relieved as shown at 40 so that the said angle iron 16 bears against the plate 16 only at its upper and lower ends 41 and 42. Thus the arrangement forms an extremely strong and rigid construction while at the same time the parts may be readily detached or separated from each other when it is desired to take down the bed for shipping or storage purposes.

It will be apparent to those skilled in the art that certain of the described details of construction may be modified or changed without sacrifice of efficiency, and without departing from the spirit of the invention, the scope of which should be determined by 45 reference to the appended claims.

I claim—

1. In a detachable connection for metal bedsteads, the combination of a tubular bed post, a side rail, a vertically extending angle iron mounted on the end of said side rail and having a longitudinally extending flange provided with a depending inclined tongue, a transversely extending member on said post adapted to wedgingly engage said tongue, a second angle member secured to the other flange of said first angle member, and a brace connecting said second angle member to said rail.

2. In a detachable connection for metal bedsteads, the combination of a tubular bed

post, a side rail, a vertically extending angle iron mounted on the end of said side rail and having a longitudinally extending flange provided with a depending inclined tongue, a transversely extending member on said post adapted to wedgingly engage said tongue, a second angle member secured to the other flange of said first angle member, a brace connecting said second angle member to said rail, said two angle members being 75 respectively provided with outwardly extending lugs, a cross piece interlocked with said lugs and a spring mattress resiliently connected to said cross piece.

3. In a detachable connection for metal 80 bedsteads, the combination of a bed post, a side rail, a vertically extending angle iron mounted on the end of said side rail and having a longitudinally extending flange, a member on said post wedgingly connected 85 to said flange, a second angle member secured to the other flange of said first angle member and an oblique brace connecting said second angle member to said rail.

4. In a mattress frame the combination of 90 a side rail, a vertically extending angle iron mounted on the end of said side rail, and having a longitudinally extending flange, a second vertically extending angle member secured to the other flange of said first angle member, an oblique brace connecting one of 95 said angle members to said rail, a cross piece interlocked with the upper ends of said angle members and a bed fabric resiliently connected to said cross piece.

5. In a mattress frame, the combination of a side rail, a vertically extending angle iron mounted on the end of said side rail, and having a longitudinally extending flange, a second angle member secured to the other 105 flange of said first angle member, a brace connecting the upper end of one of said angle members to said rail, said second angle member being provided with outwardly extending projections, an angle iron cross piece 110 having a flange perforated to admit said lugs, and a bed fabric having one of its ends connected to another flange of said cross piece.

6. In a bed structure, the combination of 115 a riser comprising an upright length of angle iron having one flange extending transversely of the bed and the other flange extending longitudinally thereof, said transverse flange being provided with an opening 120 therethrough at the bottom, adjacent the other flange, a side rail having an end extension inserted through and projecting beyond said opening, and means for securing said projecting extension to the longitudinally extending flange.

7. In a bed structure, the combination of a tubular post having an aperture in the wall thereof, a connector having a looped portion inserted into the post through the 130

- aperture and locked therein and having laterally spaced, enlarged extremities at the exterior of the post connected by a cross pin, an elongated bearing plate extending longitudinally of and clamped against the exterior of the post by the connector, a side rail having a riser secured to the end thereof, and means on the riser wedgingly engaging said cross pin so as to force the riser against the elongated bearing plate and exert an outward pull on the connector.
8. In a bed structure, the combination of a post, an elongated bearing plate extending longitudinally of and clamped against the exterior of the post, a side rail having a riser at the end, means detachably connecting the riser with the post so as to clamp the riser against the bearing plate, and a side wing on the bearing plate extending away from the post at the side of and concealing said connecting means.
9. In a bed structure the combination of a tubular side rail having the end thereof flattened, a short length of angle iron extending upwardly from and having the lower end of one flange thereof secured flat against the end of the tubular side rail, an angle iron cross member having a horizontal flange extending over the upper end of the first mentioned angle iron and having a vertical flange depending therefrom along side and secured to the first mentioned angle iron, and a bed bottom connected to said cross member.
10. In a bed structure the combination of a post having a connector on the side thereof, a side rail having an upright angular member on the end with a vertical flange projecting beyond the end of the side rail, said flange being provided with an angular notch extending inwardly from the outer edge thereof, and wedgingly engaging the connector on the post so as to clamp said angular member onto the post.

DON CARLOS TRAVIS.
